UNITED STATES PATENT OFFICE.

OSBERT S. BURKE, OF CHICAGO, ILLINOIS, ASSIGNOR TO FEDERAL ELECTRIC COMPANY, OF CHICAGO, ILLINOIS, A CORPORATION OF ILLINOIS.

SIREN-CONTROL SYSTEM.

Application filed April 10, 1922. Serial No. 551,005.

To all whom it may concern:

Be it known that I, OSBERT S. BURKE, a citizen of the United States, residing at Chicago, in the county of Cook and State of Illinois, have invented a certain new and useful Improvement in Siren-Control Systems, of which the following is a specification.

My invention relates to signalling apparatus and is primarily adapted for manually controlled fire alarm systems. The object of the invention is to make it practicable to employ a siren as the sound-producing mechanism. A siren is a well-known piece of sound-producing apparatus having a rotor capable of rotating at high speed to produce vibrations in the atmosphere for the production of sound. It is usual to drive the rotor by means of an electric motor. In giving audible fire alarm signals the common practice is to employ code numbers having not more than two digits of a value of not over 5 each, which of course permits the sending of 55 different signals. Where the signals are given by bells, as has been common practice heretofore, the bell is struck a number of times corresponding to the first digit of the signal number, then there is a pause and then the bell is struck a number of times corresponding to the second digit of the signal number. When the signal number is thus completed it is usually repeated after about 10 seconds or some interval longer than the one which occurs between the two digits of the signal number. The object of the repetition, of course, is to give the listeners an opportunity to check the signal and see that they have correctly interpreted it. Each repetition is referred to as a "round" and as stated, it is customary to give at least two rounds. In these manually operated systems call boxes are distributed throughout the territory to be protected and when a signal is to be sent in the operator "pulls" the nearest box. All he has to do is to pull a hook or rotate a handle and then release it, after which the signal is given automatically. Such boxes, commonly known as fire alarm boxes, are well-known articles of commerce and need not be described. It has been found by practical experience that there is a natural time limit during which the full number of rounds should be completed. The boxes themselves

are limited from a practical standpoint in 55 the time that they can maintain action after a single setting. These limitations are practical rather than theoretical, but nevertheless need to be taken into consideration. Another and more important consideration 60 arises from the fact that in the case of fire or other emergency, time is of utmost importance and the quicker the signal can be run off the better. Experience in this country teaches that the rounds should be run off in a period not to exceed 2½ minutes or thereabouts. In using a bell or a whistle capable of giving short, sharp blasts, no difficulty is ordinarily experienced in completing the rounds within this period. A 70 siren has certain advantages over a bell or whistle, especially in that it is a rugged and reliable piece of apparatus and capable of emitting a large volume of sound, but so far as I am aware a siren has not heretofore 75 been employed for such purpose, one reason being that owing to the weight and inertia of the moving parts the rotor could not be started and stopped with sufficient promptness to make a siren available for the purpose. My object is to overcome this difficulty and render it practicable to employ a siren for signalling under the conditions described.

I accomplish this object by the mechanism 85 illustrated in the accompanying drawings, in which—

Figure 1 is a diagram showing the application of the invention to a 3-phase power circuit.

Figures 2 and 3 are similar to Figure 1 but show the parts in changed position.

Figure 4 is a diagrammatic view showing the principle of operation of the reversing switch in the 3-phase system shown in Figures 1, 2 and 3.

Figure 5 is a diagrammatic view showing the invention as applied to a direct current system.

Figure 6 is a diagram similar to Figure 100 5 but showing the parts in changed position.

Like numerals denote like parts throughout the several views.

Referring first to the 3-phase alternating 100 current type of apparatus shown in Figures 1 to 4:

1 represents the siren having three motor

terminals *a*, *x*, *y*. As electric-driven sirens are well-known, they need not be here described except to say that in my apparatus the siren motor is subjected to somewhat greater electrical stresses than usual and hence it is desirable that the motor be built with special ruggedness, the conductive elements being preferably built of solid copper. The main supply conductors *A*, *B*, *C* supply the electric energy for driving the siren motor. This motor is controlled by a reversing switch which in actual practice is preferably in the form of a drum controller, but which for explanatory purposes I have illustrated as comprising a rotatable shaft having three sections 5, 6, 7 insulated from each other. On section 5 are three conductive discs 10, 11, 12. On section 6 are three conductive discs 15, 16, 17. On section 7 are two conductive discs 19, 20, which form the movable elements of a maintaining switch.

Each disc in the order named has its respective contactor 21, 22, 23, 24, 25, 26, 27, 28. Discs 10, 15 and 19 are continuously conductive. Discs 11, 12, 16, 17 and 20 have insulating segments 31, 32, 33, 34 and 35 respectively. The angular extent of these discs will be hereinafter explained. Contactor 21 is connected by a conductor 40 to supply conductor *C*. Contactor 22 is connected by conductors 41 and 42 to motor terminal *x*. Contactor 23 is connected by conductors 43 and 44 to motor terminal *y*. Contactor 24 is connected by conductor 45 to supply conductor *B*. Contactor 25 is connected by conductors 46 and 44 to motor terminal *y*. Contactor 26 is connected by conductors 47 and 42 to motor terminal *x*. The supply conductor *A* is connected by conductor 48 to motor terminal *a*. Contactor 27 is connected by conductors 50 and 51 to the stationary contact 52 of a relay presently to be described. Contactor 28 is connected by conductors 53 and 54 to relay switch arm 55.

The shaft of the reversing and maintaining switches is driven by a worm wheel 60 engaged by a worm 61 fastened to shaft 62 of a motor 63. For identification this will be referred to as the "controller" motor. In practice it is of a very small size, for example, 1/20 H. P., its function being merely to drive the drum controller (reversing switch), which has just been described. Said controller motor is connected by a conductor 66 to one end of a battery 67 or other source of electric energy, the other terminal of the battery being connected by a conductor 68 to the conductor 51. It will thus be evident that when the relay switch arm 55 is closed the controller motor 63 will be driven by the energy derived from the battery 67.

The relay switch arm 55 is controlled by an electromagnet, having an armature 70,

which actuates arm 55 and is in position to be magnetically controlled by the core 71 of a winding 72. A tension spring 73 normally holds the armature in open position. The movement is limited by means of a stop 74. One end of the coil 72 is connected by a conductor 76 to a battery 77. The remaining end of the coil and the remaining end of the battery are connected by conductors 78 and 79 respectively to what may be termed the "district circuit," by which I mean the circuit running to the districts where the manual devices or "boxes" are distributed. I have illustrated the external circuit in accordance with common and well-known practice, in which the circuit is normally closed and the signalling device (which in my case is the siren) operates only when the circuit is open. I have also selected, to illustrate the manually operated devices, a typical fire alarm box, the principles and construction of which are well-known. According to this system a plurality of boxes *P*, *Q*, *R* are arranged in series, and it will be understood, of course, that any number of such boxes, within reasonable limits, may be employed. I have illustrated these boxes more or less diagrammatically. In the form illustrated each box has an arm 80, which presses toward a rotatable disc 81. This arm also constitutes one element of a switch, electrically connected to the conductor 78 and adapted to electrically engage a stationary contact 83 located within the box. Contact 83 is electrically connected by a conductor 84 to an arm 80 in the adjacent box, and this arrangement is repeated, thus placing all of the boxes in series and normally maintaining a closed circuit.

Each disc 81 previously mentioned has teeth 86 adapted to lift its arm 80 so as to break contact with the stationary switch element 83. The disc rotates slowly with the result that the arm is alternately raised and lowered, and the contact correspondingly broken and established, thus de-energizing and energizing the coil 72 of the relay and energizing and de-energizing the controller motor 63. As the internal construction of call or signal boxes is so well-known, detailed description of the means for rotating the disc is not necessary further than to say that each disc has a pinion 90 fastened to it, which meshes with a gear wheel 91, the latter being driven by a spring 92, one end of which is fastened to the gear and the other to a lever or handle 93. The number of gears in this train may, of course, be varied. The parts are prevented from rotating too rapidly by an escapement consisting of a pinion 95, which meshes with gear 91 and is fastened to an escapement wheel 96, which co-operates with an oscillating pawl 97 fastened to a swinging pen-

dulum 98. The parts are so constructed that when the operator "pulls" the handle 98 from the upright position shown in Figure 1 to a downright position and then releases it, the disc 81 will be caused to rotate slowly in the proper direction to raise and lower the arm 80. According to common practice the parts are so timed that the disc will make two complete rotations or 10 "rounds," thus causing the signal to be given once and then repeated.

Operation.—In Figure 1 I have shown the normal or "at rest" position of the parts. The reversing switch holds the siren motor 15 de-energized, insulating segments 31, 32, 33 and 34 being in engagement with their respective contactors 22, 23, 25 and 26. The insulating segment 35 is in engagement with contactor 24 and switch arm 55 of the relay 20 is open. Thus the controller motor 63 is on open circuit and the controller stands still. If, now, an alarm is to be sounded, a person approaches one of the call boxes P, Q, R, "pulls" the lever 98 and then releases it. This starts the disc 81 within the box to rotating slowly. As soon as one of the teeth 86 comes under the arm 80 and raises it, the latter breaks contact with the stationary switch element 83, thus de-energizing the coil 72 and permitting the spring 73 to close the switch arm 55 of the relay. As soon as this arm closes, current is supplied to the controller motor 63 by the battery 67. This starts the motor, 30 which rotates worm 61, wheel 60 and shaft 5, 6, 7. The rotation of this shaft causes the reversing switch to operate. The shaft makes a complete revolution for each of the teeth 86 of the particular box which has been "pulled." Each single rotation of the reversing switch causes a starting, driving and stopping of the siren motor. In other words, each tooth on the disc of the "pulled" 40 box will cause an individual blast from the siren. The angular extent and location of the insulating segments of the reversing switch is such as to first establish the circuit through the siren motor, then reverse the connections of the x , y terminals, and 45 then disconnect the motor, thus causing a starting, running, retarding and de-energizing of the motor for each complete rotation of the discs. The reversing of the x , y terminals is illustrated with a conventional 50 diagram in Figure 4, where it will be seen that the reversing switch S will at one time connect the main conductor B to the motor terminal x , and the main conductor C to the motor terminal y , and then reverse 55 the motor connections and connect the supply conductor B to the motor terminal y , and the supply conductor C to the motor terminal x . Differently stated, the reversing switch causes an interchange in the 60 connections of the B, C supply conductors 65

and the x , y motor terminals. The supply conductor A is at all times connected to the motor terminal a . It will be understood that by thus reversing two of the leads the motor will be reversed and the retardation 70 of the siren will be rapidly accomplished. The fact is that in actual practice I have found it practicable to produce 5 separate and individual blasts with a suitable interval between each blast in about 55 seconds. 75 I have found that whereas it requires about three seconds to obtain full speed from rest, the siren may be brought from full speed to rest in about one second. It is desirable to give a longer interval between two rounds 80 than between two blasts, for example, a period of about 10 seconds between rounds (that is before repeating the signal) is appropriate, and I have, therefore, found that with my apparatus a period of 2½ minutes 85 is ample time for giving a complete signal and a complete repetition thereof.

To describe in detail the operation of the reversing switch and maintaining switch: The normal or "at rest" position has already been described and is illustrated in Figure 1. Let it be assumed that when the parts are in this position the district circuit which controls the relay switch arm 55 is opened as a result of the pulling of the box. The 95 control motor 63 becomes energized from the battery 67 or other suitable source of electric energy (it being possible, of course, to obtain such energy from the main supply conductors if desired). The controller 100 shaft 5, 6, 7 rotates in the direction of the arrows, that is, clockwise according to the present drawings, and after a short interval the insulating segments 31 and 33 will pass beyond their respective conductors 22, 25 105 whereupon the parts will assume the position shown in Figure 2 and the siren motor will be put on closed circuit as follows:

The supply conductor A is connected to the motor terminal a through the conductor 110 48. The motor terminal x is connected to the supply conductor C as follows: through the conductors 42 and 41 to the contactor 22, thence to the disc 11, shaft 5, disc 10, contactor 21 and conductor 40 to said supply 115 conductor C. The terminal y is connected to the supply conductor B through the conductors 44 and 46, contactor 25, disc 16, shaft 6, disc 15, contactor 24 and conductor 45 to supply conductor B. About this time 120 the maintaining switch comes into operation to maintain the circuit through the control motor 63 so that said motor will keep on rotating even though the relay switch arm 55 may return to normal open position. The 125 maintaining switch goes into action when the insulating sector 35 has rotated past the contactor 28 whereupon the circuit through the motor will be completed as follows: from the disc 20 to contactor 28, thence 130

through conductor 53 to one of the terminals of motor 63. The other terminal is connected through the conductor 66 through the battery 67 or other source of electrical energy, thence through the conductors 68 and 50 to the contactor 27, thence through the disc 19 and shaft 7 to the said disc 20. Thus the shaft is kept rotating until the segment 35 again comes into engagement with the contactor 28 whereupon the shaft will come to rest with the siren motor on open circuit as shown in Figure 1.

After the siren motor has rotated for a sufficient period to give a single blast and 15 the time comes when it should come to rest, this requirement is accomplished through the medium of the circuit changer or reversing switch, which causes a reversal of the connections of the x, y terminals and the B, 20 C supply conductors. Figure 3 illustrates the position of the reversing switch during this period of retardation and stoppage of the motor. To trace the circuits: the supply conductor A remains connected to the motor 25 terminal a as before. The supply conductor B is connected to the motor terminal y as follows: through the conductor 45, contactor 24, disc 15, shaft 6, disc 17, contactor 26 and conductors 47 and 42. The supply 30 conductor C is connected to the motor terminal x as follows: through the conductor 40, contactor 21, disc 10, shaft 5, disc 12, contactor 23 and conductors 43 and 44. This reversal of the connections of the siren 35 motor causes the latter to come to rest very quickly, for example, in about a second, whereupon the parts reach the position shown in Figure 1 and the motor will remain at rest unless and until another tooth 40 86 opens the district circuit (through the relay coil 72).

It will thus be seen that the action is automatic after the box has been pulled and with 45 my apparatus the siren will be controlled in such manner as to give comparatively short and distinctly individual blasts, which may be readily distinguished and counted by any one within hearing of the siren.

In the foregoing I have described the invention as applied to an alternating current power circuit. In Figures 5 and 6 I have 50 illustrated the invention as applied to a direct current power circuit. In this instance the siren motor is arrested by short circuiting the armature upon itself. This produces a dynamic braking and brings the siren promptly to rest. Referring to Figures 5 and 6, the alarm boxes, relay and maintaining switch are the same as before. 55 The reversing switch and motor connections, however, are different and will now be described.

Section 7 of the shaft is fastened to but 60 insulated from a shaft section 100. Fas- 65 tened to this section 100 are three discs 101,

102, 103, which are of conductive material and co-operate respectively with contactors 106, 107, 108. These discs as in the previous case diagrammatically illustrate a drum controller, which is the apparatus used in practice. On the disc 101 is an insulating segment 110 and on the disc 103 is an insulating segment 111. The supply conductor D is connected by a conductor 114 to contactor 106. The component supply conductor E of opposite polarity is connected by a conductor 116 to the contactor 108. The contactor 107 is connected by a conductor 118 to one of the terminals of the motor 119 of the siren 120. The other motor terminal is connected by a conductor 122 (preferably through a small resistance 123) to the conductor 116. The field coil 126 of the siren motor is connected across the line by the conductors 127 and 128. This is intended to represent the conventional connection and it will be understood that the method of energizing the field coils may be varied without departing from the spirit of the invention.

When the parts are at rest the insulating segments 110 and 111 will be in engagement with their respective contactors 106 and 108. This normal or "at rest" position is not specifically illustrated in the drawings, as Figure 5 shows the parts as they will appear after the siren motor has started. With the contactors 106 and 108 engaging insulating segments the siren motor will, of course, be disconnected from the power circuit. After the reversing switch has been rotated to the position shown in Figure 5, the siren motor will be energized as follows: from the supply conductor D through the conductor 114, contactor 106, disc 101, shaft 100, disc 102, contactor 107, conductor 118 to one of the motor terminals, thence through the motor to the other terminal, thence through conductor 122, resistance 123 (if present) and conductor 116 to the opposite side E of the line. This condition continues until the time approaches to cut off the blast, whereupon the insulating segment 110 reaches the contactor 106, thus disconnecting the motor from one side of the line. After this condition has been maintained for a moment, the insulating segment 111 comes to the end of its reach, passing out of engagement with the contactor 108 and permitting the latter to engage the disc 103. This causes short circuiting of the armature upon itself with consequent dynamic braking. The circuit through the armature may be traced thus: from one of the armature terminals through the conductor 118, contactor 107, disc 102, shaft 100, disc 103, contactor 108, conductor 116, resistance 123 (if present) and conductor 122. This short-circuiting of the armature permits the passage 125

of a very large current, which causes a very rapid deceleration of the rotating parts in accordance with well-known principles.

From the above it will be seen that in either type, alternating or direct current, by changing the motor connections the rotor of the siren is brought quickly to rest and this makes it possible to produce a number of individual and readily distinguishable blasts for sending out the required signal. As the operation is so largely electric in its nature, the apparatus may be readily kept in order and will require little attention, and at the same time will emit an audible signal having great volume of sound.

While I have illustrated the invention as embodied in a three-phase alternating current system and in a direct current system, it is also possible to apply it to a single phase system as shown in my copending application filed August 24, 1922, Serial No. 583,982 but whether the siren motor is of the single-phase or poly-phase type it is, according to my invention, controlled by a phase changer, as recited in some of the appended claims.

Having thus described my invention, what I claim is new and desire to secure by Letters Patent is:

1. A signalling system of the type described having a siren provided with a rotatable sound producing element, an electric motor for driving it, and means including a circuit changer for supplying electrical energy to said motor for causing it to rotate in one direction in one position of the circuit changer and for changing electromagnetic conditions in the motor in another position of the circuit changer to produce a magneto motive force opposing such rotation.

2. A signalling system for giving short audible blasts, said system having a siren provided with a rotary sound producing element and an electric motor for driving it, means including circuit conductors and switch elements for supplying electrical energy to said motor for causing it to rotate in one direction in one position of the switch elements and for changing electromagnetic conditions in the motor in another position of the switch elements, electromagnetic means for operating said switch elements, and means for controllably energizing said electromagnetic means.

3. A signalling system of the type described having a siren provided with a rotatable sound producing element, an electric motor for driving it, means including a circuit changer for supplying electrical energy to said motor for causing it to rotate in one direction in one position of the circuit changer and for changing electromagnetic conditions in the motor in an-

other position of the circuit changer to produce a magneto motive force opposing such rotation, and means including a code wheel fire-alarm box and a circuit therefor for operating said circuit changer.

4. Apparatus for giving audible code signals having a siren provided with a rotary sound producing element, an electric motor connected to it for rotating it, and means for supplying electrical energy to said motor, said means including circuit conductors and a rotary circuit changer which in one angular position establishes a circuit to produce a magneto-motive force to rotate the rotary element of the motor in one direction, and in another angular position establishes a circuit to produce a magneto motive force in the motor to oppose such rotation, and driving means for rotating said circuit changer.

5. A signaling system for emitting short audible blasts, having a siren provided with a rotor for producing the sound and an electric motor having a rotating armature positively connected to said sound producing element for accelerating and retarding it, a source of alternating current, and means for altering the phase relation between the field and armature windings to thereby at times rotate the armature and at other times create electromagnetic opposition within the motor windings to the rotation of the armature, thus to bring it and the siren rotor promptly to rest.

6. A system for giving audible code signals having an electric motor, a siren having a rotary sound producing rotor rigidly connected to the rotor of the motor, and means including a rotary circuit changer for supplying electrical energy to said motor for causing it to rotate in one direction in one angular position of the circuit changer and for changing electromagnetic conditions in the motor in another angular position of the circuit changer to produce a magneto motive force opposing such rotation.

7. A system for giving audible code signals having an electric motor, a siren having a rotor connected to and driven by the rotor of said motor, means including a rotary circuit changer for supplying electrical energy to said motor for causing it to rotate in one direction in one angular position of the circuit changer and for changing electromagnetic conditions in the motor in another angular position of the motor, a power device for rotating the circuit changer and means for controlling said power device to cause it to impart full angular movement of said circuit changer.

8. A system for giving audible code signals having a siren with a rotary sound producing element, an electric motor directly connected to it for driving it, a rotary cir-

cuit changer, a source of electrical energy and circuit conductors connected to said source and to the motor and controlled by said circuit changer whereby in one angular position of the circuit changer the motor will be supplied with electrical energy to cause it to rotate in one direction and in another angular position will change the

electromagnetic conditions in the motor to oppose such rotation, a power device for 10 rotating said circuit changer, and means including a code wheel box for controlling said power device.

In witness whereof, I have hereunto subscribed my name.

OSBERT S. BURKE.
